DESIGN FOR A CONTAINER CAP OR SIMILAR ARTICLE

George Pavlinetz, Carteret, N. J.

Application November 28, 1947, Serial No. 142,865

Term of patent 14 years

(Cl. D58—26)

To all whom it may concern:

Be it known that I, George Pavlinetz, a citizen of the United States, residing at Carteret, in the county of Middlesex, and State of New Jersey, have invented a new, original, and ornamental Design for Container Cap or Similar Article, of which the following is a specification, reference being had to the accompanying drawing, forming part thereof.

Figure 1 is a plan view, Figure 2 is a side elevation and Figure 3 is a section taken along line 3—3 of Figure 2 of a container cap or similar article, showing my new design.

I claim:
The ornamental design for a container cap or similar article, as shown.

GEORGE PAVLINETZ.
